UNITED STATES PATENT OFFICE

2,524,543

MOUNTING FOR DETACHABLE PRINTING BARS

Commodore D. Ryan and Edward P. Drake, Los Angeles, Calif., assignors to Commercial Controls Corporation, a corporation of Delaware

Original application June 16, 1944, Serial No. 540,728. Divided and this application January 19, 1945, Serial No. 573,516

6 Claims. (Cl. 101—109)

1

This invention relates to printing mechanism and more particularly to printing mechanism for use in the rotatable printing head of the meter of a metered mailing machine.

One of the objects of this invention is to provide printing mechanism which is simple, practical and thoroughly durable. Another object is to provide new and improved printing mechanism. Another object is to provide mechanism of the above character in which the printing die may be readily changed. Another object is to provide mechanism of the above character which is characterized by its simplicity of construction. A further object is to provide mechanism of the above character for a rotatable printing head which is easily set at either printing or non-printing positions. Still another object is to provide mechanism of the above character in which efficient means is provided to hold the printing element in either printing or non-printing position. Other objects will be in part obvious and in part pointed out hereinafter.

The invention accordingly consists in the features of construction, combinations of elements, and arrangements of parts, all as will be illustratively described herein, and the scope of the application which will be indicated in the following claims.

Referring now to the accompanying drawings, in which is shown one of the various possible embodiments of this invention:

Figure 1 is a side elevation of the rotatable printing head of a meter of a metered mailing machine;

Figure 2 is an end elevation of the rotatable printing head shown in Figure 1 taken on the line 2—2 of Figure 1, the removable portion of the head being separated from the body of the head;

Figure 3 is a horizontal section taken on the line 3—3 of Figure 2;

Figure 4 is a vertical section taken on the line 4—4 of Figure 5; and,

Figure 5 is a vertical section taken on the line 5—5 of Figure 1.

Similar reference characters refer to similar parts throughout the several views of the drawings.

This application is a division of the copending application of Commodore D. Ryan and Edward P. Drake, which bears Serial No. 540,728, and which was filed on June 16, 1944.

As conducive to a clearer understanding of certain features of this invention, it might here be pointed out that the printing mechanism to be

2

described hereinafter is particularly adapted for use in the rotatable printing head of the meter of a metered mailing machine. There is certain printed matter which must appear on certain stamps printed by the meter, such as "Section 562 P. L. & R." on third class mail, which does not appear on other stamps or on stamps of first and second class mail. Furthermore, there is a possibility that changes in the postal laws may require printed matter different from that now used on stamps to be used in the future. Thus, it is an object of this invention to provide a printing die which may be readily moved between printing and non-printing positions and also readily interchanged with other printing dies carrying different printing matter. Difficulty in accomplishing these objects is encountered due to the fact that the sides of the printing head of the meter of a metered mailing machine are covered by a housing to prevent the taking of fraudulent impressions from the stamp dies. Thus, the only readily accessible place for operating and interchanging such a printing die is the outer end of the printing head. Accordingly, it is another object to overcome the above-mentioned difficulties as well as many others.

Rotatable printing head 10 (Figure 1) is cylindrically shaped (Figure 4), is mounted on a shaft 11 (Figure 1), and is cyclically driven through shaft 11 as shaft 11 is turned during the operation of the meter. A portion of the meter is shown in Figure 1 and is generally indicated at 12. Printing head 10 turns in the direction of the arrow in Figure 4 and has a printing element generally indicated at 13 thereon. Printing head 10 is enclosed in a housing diagrammatically indicated at 20 (Figure 4) which covers the sides of the head with the exception of a hole in its lower portion to permit the printing dies on the head to coact with the platen diagrammatically indicated at 15 (Figure 5) to print upon matter positioned between the platen and the head. This housing has another opening therein to permit access to the outer end 13a of the printing element 13 (Figure 1). When the printing head is in "rest" position, the die 16 on printing element 13 (Figure 4) and other portions of the stamp dies, generally indicated at 21 are covered by housing 20. This prevents the taking of fraudulent impressions from the stamp dies when the meter is in "rest" position.

The mechanism in head 10 (Figure 4) is mounted on two parallel supporting plates 23 and 24 which are secured to the outer end of shaft 11. Printing element 13 (Figures 4 and 5)

55

is flat with the exception of the upwardly extending portion 13b which carries the printing die 16. The lower edge of element 13 curves downwardly to a portion 13c of element 13 which has a slot 25 therein. The mouth of slot 25 opens downwardly, as viewed in Figure 5, and it will be noted that slot 25 slants slightly to the right as viewed in this figure. This aids in the removal of element 13 from the printing head 10, as will be described more fully hereinafter. The outer edges of element 13 at the mouth of slot 25 are beveled outwardly away from each other to aid in mounting element 13 on a pivot pin, generally indicated at 26.

Pivot pin 26 has two enlarged portions 26a and 26b (Figure 1) thereon on opposite sides of the portion of pin 26 on which element 13 is pivotally mounted. The juxtaposed faces of enlarged portions 26a and 26b are beveled toward the axis of pin 26 to aid in guiding the portion 13c and its slot 25 of element 13 into operating relationship with respect to pin 26. Pin 26 is secured to supporting plate 24 in any suitable manner, such as by a reduced portion (not shown) which extends through plate 24 and then is headed.

A lever, generally indicated at 30 (Figure 5), resiliently urges movement of element 13 in a clockwise direction or from a printing to a non-printing position. This lever is in the form of a bellcrank which is pivotally mounted on pin 26 (Figures 1 and 5). The lower end of lever 30 extends to the left as viewed in Figure 4 and is connected by a spring 31 to a lug 24a on plate 24. The upper arm 30a of lever 30 is aligned with and abuts against the upwardly extending portion 13b of element 13 (Figures 4 and 5). Thus as spring 31 urges arm 30b of lever 30 downwardly, arm 30a of lever 30 resiliently urges movement of element 13 in a clockwise direction, as viewed in Figure 5.

To aid in mounting element 13 on the rotatable printing head 10, a guide member 33 is provided. The lower portion 33a (Figure 5) of this member is secured to supporting plate 24 by rivets 34. The upper portion 33b of member 33 curves outwardly and thence upwardly. This portion of member 33 slants upwardly to the left, as viewed in Figure 5, and is so positioned that it acts as a chute to guide the inner end of element 13 when element 13 is being inserted or removed from the printing head.

Element 13 is held in printing or non-printing position and its removal from the printing head is controlled by a latch member, generally indicated at 40 (Figure 2). The outer end 13a of element 13 extends through a slot 41 in the end wall of the printing head and the body of element 13 is inserted into or removed from head 10 through slot 41. Latch member 40 is pivotally mounted on a pin 43 connected to end wall 42 and is resiliently urged in a clockwise direction by a spring 44 which is also mounted on pin 43. One of the ends of spring 44 bears against a forwardly extending portion 40a of latch member 40 (Figure 3) and also against a portion 45 of the printing head housing. Latch member 40 has a finger piece 40b (Figure 2) which extends through a slot 46 in end wall 42, thus permitting member 40 to be manually moved in a clockwise direction against the action of spring 44. When element 13 is in printing position, as viewed in Figure 5, then it is supported by a lug 48 (Figure 2) extending to the left from the right-hand edge of slot 41 as element 13 is held against the right-hand edge 41 by latch member 40.

When it is desired to move element 13 to a non-printing position, the user moves the end portion 13b of element 13 to the left, as viewed in Figure 2. Movement in this direction is permitted because slot 41 is wider than the thickness of element 13. After element 13 has been moved to the left, then it can be moved downwardly past lug 48 by spring 31 until it strikes a lug 50 on latch member 40. Latch member 40 then resiliently urges the end portion 13b of element 13 to the right, as viewed in Figure 2, into engagement with the right-hand edge of slot 41. At this time it is held in a non-printing position between lugs 48 and 50.

If it is desired to change element 13 and replace it with one having a different die, finger piece 40b is used to move lug 50 from beneath element 13. This permits spring 31 to move element 13 to the position indicated by the dotted line 60 in Figure 5. When the element 13 is in this position, its inner end may be moved upwardly to free the connection between slot 25 and pin 26. Then element 13 may be withdrawn from the printing head through slot 41 (Figure 2). When the new element is inserted, latch member 40 is held to the left, as viewed in Figure 2, and the chute portion 33b of guide member 33 guides the inner end of element 13 into position on pin 26. Once the element is pivotally mounted on pin 26, it may be moved either to a printing or non-printing position.

Thus a thoroughly efficient and practical printing mechanism has been disclosed in which the printing die may be moved to and retained in either printing or non-printing positions. Furthermore, the printing element is easily removable from the machine so that another one may be substituted for it. Accordingly it will be seen that the objects hereinabove referred to, as well as many others, are successfully accomplished.

As many possible embodiments may be made of the mechanical features of this invention, and as many changes might be made in the embodiment above set forth, it is to be understood that all matter hereinbefore set forth, or shown in the accompanying drawings, is to be interpreted as illustrative and not in a limiting sense.

We claim:

1. In mechanism of the type described, in combination, a printing head, a printing element having an open-ended slot therein, a pivot pin mounted on said printing head, said printing element being detachably mounted on said pivot pin by means of said slot, a pivotally mounted member, said member engaging said printing element, spring means for resiliently urging said member to move in a direction in which it resiliently urges movement of said printing element out of printing position, a catch for locking said printing element both in and out of printing position, and a chute for guiding said printing element into engagement with said pivot pin as it is mounted on said printing head.

2. In mechanism of the type described, in combination, a rotatable printing head, a printing element extending longitudinally of the axis of rotation of said printing head, a pivot pin mounted on said printing head, means forming a slot in said printing element adjacent one end thereof, said slot having one end open, said slot slanting downwardly and outwardly toward the axis of rotation of said head and the end of said printing element, means permitting said printing element to be manually moved between printing and removal positions, and a catch for holding

said printing element in printing position, the free end of said printing element being moved toward the axis of said printing head when said printing element is moved into removal position, said pivot pin coacting with said slot to prevent removal of said printing element except when said printing element is in removal position.

3. In mechanism of the type described, in combination, a rotatable printing head, a printing element extending longitudinally of the axis of rotation of said printing head, a pivot pin mounted on said printing head, means forming a slot in said printing element adjacent one end thereof, said slot having one end open, said slot slanting downwardly and outwardly toward the axis of rotation of said head and the end of said printing element, the other end of said printing element extending from one end of said printing head to permit said printing element to be manually moved into and out of printing position, and a catch for holding said printing element in printing, non-printing, or removal position, the free end of said printing element being moved toward the axis of said printing head when said printing element is moved into removal position to substantially align said slot longitudinally with respect to the axis of said printing head, said pivot pin coacting with said slot to prevent removal of said printing element except when said printing element is in removal position, said printing element being moved longitudinally of said printing head when it is removed therefrom, spring means for resiliently urging said printing element out of printing position, and a channel-shaped guide member for guiding the slotted end of said printed element into engagement with said pivot pin when it is being mounted on said rotatable printing head.

4. In mechanism of the type described, in combination, a rotatable printing head, a printing element extending longitudinally of the axis of rotation of said printing head, a pivot pin mounted on said printing head, means forming a slot in said printing element adjacent one end thereof, said slot having one end open, said slot slanting downwardly and outwardly toward the axis of rotation of said head and the end of said printing element, means permitting said printing element to be manually moved between printing and removal positions, a catch for holding said printing element in printing position, the free end of said printing element being moved toward the axis of said printing head when said printing element is moved into removal position, said pivot pin coacting with said slot to prevent removal of said printing element except when said printing element is in removal position, a member pivotally mounted on said pivot pin, a portion of said member engaging said printing element, and a spring connected to said member and said head, said spring acting through said member to resiliently urge said printing element out of printing position.

5. In mechanism of the type described, in combination, a rotatable printing head, a printing element extending longitudinally of the axis of rotation of said printing head, a pivot pin mounted on said printing head, means forming a slot in said printing element adjacent one end thereof, said slot having one end open, said slot slanting downwardly and outwardly toward the axis of rotation of said head and the end of said printing element, the other end of said printing element extending from one end of said printing

head to permit said printing element to be manually moved into and out of printing position, a catch for holding said printing element in printing, non-printing, or removal position, the free end of said printing element being moved toward the axis of said printing head when said printing element is moved into removal position to substantially align said slot longitudinally with respect to the axis of said printing head, said pivot pin coacting with said slot to prevent removal of said printing element except when said printing element is in removal position, said printing element being moved longitudinally of said printing head when it is removed therefrom, spring means for resiliently urging said printing element out of printing position, and a channel-shaped guide member for guiding the slotted end of said printed element into engagement with said pivot pin when it is being mounted on said rotatable printing head.

6. In mechanism of the type described, in combination, a rotatable printing head, a printing element extending longitudinally of the axis of rotation of said printing head, a pivot pin mounted on said printing head, means forming a slot in said printing element adjacent one end thereof, said slot having one end open, said slot slanting downwardly and outwardly toward the axis of rotation of said head and the end of said printing element, the other end of said printing element extending through a slot in one end of said printing head to permit said printing element to be manually moved into and out of printing position, a catch for holding said printing element in printing, non-printing or removal position, said catch being mounted on said last-mentioned end of said printing head and being movable in a plane transverse to the axis of rotation of said head, said catch including lugs for holding said printing element in adjusted position, spring means resiliently urging said catch into engagement with said printing element, the free end of said printing element being moved toward the axis of said printing head when said printing element is moved into removal position, said pivot pin coacting with said slot to prevent removal of said printing element except when said printing element is in removal position, a pivotally mounted member engaging said printing element, and spring means acting through said last-mentioned member for resiliently urging movement of said printing element out of printing position.
